Primary Examiner — Bao-Yen T Nguyen

CLAIM

The ornamental design for a display screen or portion thereof with a graphical user interface for a surgical instrument, as shown and described.

DESCRIPTION

FIG. 1 is a front view of a display screen or portion thereof with a graphical user interface for a surgical instrument; and, FIG. 2 is a front view of a second embodiment of a display screen or portion thereof with a graphical user interface for a surgical instrument.

The evenly spaced broken lines illustrate a display screen or portion thereof and form no part of the claimed design. The dash-dot broken lines illustrate the boundary of the claimed design and form no part thereof. The dash-dash broken lines within the boundary illustrate portions of the graphical user interface and form no part of the claimed design.

1 Claim, 2 Drawing Sheets
